UNITED STATES PATENT OFFICE.

CHARLES F. KETTERING, OF DAYTON, OHIO, ASSIGNOR TO THE DAYTON ENGINEERING LABORATORIES CO., A CORPORATION OF OHIO.

ENGINE-STARTING DEVICE.

1,184,858.

Specification of Letters Patent. Patented May 30, 1916.

Application filed June 22, 1911. Serial No. 634,657.

To all whom it may concern:

Be it known that I, CHARLES F. KETTERING, a citizen of the United States, residing at Dayton, county of Montgomery, and State 5 of Ohio, have invented certain new and useful Improvements in Engine-Starting Devices, of which the following is a full, clear, and exact description.

This invention relates to improvements 10 in engine starting devices, some of which are shown in my previous filed and copending applications, bearing Serial Number 621,512, filed April 17, 1911, and Serial Number 633,443, filed June 15, 1911.

15 It is one of the objects of the present invention to provide a starting system which is controlled by the spark controlling lever of the ignition system. That is, the control of the starting system is consolidated with 20 the spark lever control, such as is ordinarily used in combustion and explosive engines to advance or retard the ignition spark. That is, in the present invention the spark-control lever, in addition to performing its 25 usual functions of regulating or controlling the ignition spark, is also adapted, when adjusted to a certain position, to perform the function, assumed by the push button, in my above named copending application,

30 that is, to effect the interlocking of the clutch pedal or operating member, and the means which controls the coupling of the engine and starting device together, so that upon the movement of the clutch pedal, the

35 coupling means between the engine and starting device will be brought into operative position. This same spark lever control is also adapted to effect an initial operation of the starting device, so as to facilitate 40 the coupling up thereof to the engine. In other words, the starting device embodied in the present invention is of that type which comprises an electric motor, normally disconnected from the engine, and wherein

45 it is desirable to impart an initial movement to the motor, previous to the actual starting operation, so as to facilitate and make sure of a complete and efficient coupling up between the engine and starting device.

50 Thus the spark-control lever, when moved in one direction slightly beyond its home or normal position, may be utilized to cause the initial movement of the starting device as well as said interlocking, for engine starting purposes, and the continued advance of

the same spark lever will then advance the spark of the engine, as soon as the same has been started and is operating under its own actuating power. This makes a simple and ready control of the initial starting operation of the engine, by means of the spark-lever. It is to be understood that this arrangement of the spark control lever may be utilized to perform both of these functions of causing the initial starting movement 65 and effecting the interlocking described, or it may be utilized to perform either one of these functions alone, in cases where it may not be desirable to make it perform the other function.

70 Another object is to provide against the accidental functioning of this spark lever, in case it should be moved back to this initial starting position while the engine is running. For example, it being often customary to throw the spark lever back to home position while the engine is running, if this same spark lever is utilized to control the starting operation, as described, it is desirable to prevent any such accidental 75 functioning of the lever, while the engine is running. For this reason, mechanisms are so arranged that while the engine is running, the spark lever becomes ineffective 80 when moved back to the initial starting position, so far as concerns either one of the functions of producing an initial movement 85 of the starting device or coupling up the starting device to the operating member.

88 As a still further safe guard, a stopping 90 device is provided in connection with the spark lever, so that when the lever is moved back to its home position, a latch operates to stop it in that position, so that the operator intentionally has to move this latch to 95 permit the lever to be moved still farther into its so called "initial starting position". Even though this is done while the engine is running, the other mechanism prevents the spark lever from operating as described, 100 relative to the starting system.

With these and other incidental objects in view, as will hereinafter appear, the invention consists of certain novel combinations of mechanism, the preferred form of one 105 embodiment of which is shown in the accompanying drawings and fully described in the following specification.

In the drawings, Figure 1 is a top plan view of the chassis of an automobile, certain 110

parts of the chassis and automobile being removed for the sake of clearness. This view particularly shows the relative location of the various parts of the system, embodied in the present invention. Fig. 2 is a diagrammatic view showing the electrical circuits and connections. Fig. 3 is a detail view of the steering rod and wheel of an automobile, embodying my improved means for controlling the initial movement of the motor-generator and effecting the interlocking of the connections, which, control the coupling of the motor-generator to the engine, with the main operating member, or clutch pedal. Fig. 3^a is a detail perspective view in section, of a portion of the improved switch mechanism, employed in the present invention. Fig. 3^b is a view similar to Fig. 3^a, but discloses in addition, the bracket, whereon the switch casing is mounted, together with the means for effecting the opening and closing of the switch. Fig. 4 is a detail view in side elevation of the electrically controlled interlocking mechanisms, which are normally loosely mounted upon the clutch shaft of the automobile. This view also shows a pivoted or latch mechanism in engaging position with the curved arm, which is rigidly carried by the clutch shaft. Fig. 5 is a view similar to that of Fig. 4, but taken from the opposite side of said mechanism, the pivoted armature in this instance, being shown in disengaged position. Fig. 6 is a fragmentary top plan view of the steering wheel, showing my improved spark control-lever. Fig. 6^a is a detail view of the spark control-lever and its coöperating sector or quadrant removed from the steering wheel. Figs. 7 and 7^a are modified forms of the spark control-lever and the coöperating sector. Fig. 8 is a detail top plan view of the multiplied gearing for coupling the motor-generator and the engine, with the connections for controlling the actuation thereof. This view also shows the rod connected with the controller for shifting the controller from starting to charging position and vice versa. Fig. 9 is a fragmentary detail view of the coupling gearing in coupled position. Figs. 10 and 10^a are detail views of the friction clutch mechanism, which couples up the motor-generator, as a generator, to the engine.

Referring to the drawings for the present, and more particularly to Fig. 1 thereof, it may be stated that the type of automobile in which this improved system is shown as applied, is a "Cadillac" which is a well known automobile on the market at the present time. In Fig. 1, the chassis of the automobile is shown having the side frames 20, which together with certain transverse supporting members, carry and support the engine 21, which is of the usual four cylinder four cycle type, employed in automobiles of

this character. The running boards on the opposite sides of the vehicle are indicated by the numerals 22 and 23 respectively. The transmission gears in the present instance are contained in the casing 24, and are controlled by means of the lever 25, which when moved back and forth, selects the various speeds forward, or the reverse speed as desired.

Mounted on the shaft 27 which is disposed substantially parallel with the crank shaft of the engine and which is normally used to operate the magneto, is an oil pump 26 which is of the same type as that heretofore used in automobiles of this character. This shaft 27, because of its location is advantageously made use of in the present system, as will appear hereinafter.

28 represents the engine fly-wheel secured in the usual manner to the engine shaft and having a series of gear teeth, formed on or secured to its periphery, as at 29.

The transmission clutch 30 is of the usual construction and is adapted to be moved into and out of engagement with the conical surface of the interior of the fly-wheel. The movement of this clutch is controlled through the medium of a yoke member 31^a, by movement of the transverse shaft 31, which may be termed the "clutch shaft," to which said yoke is secured, and the operation or movement of the ordinary clutch pedal 32, whereby the engine will be connected and disconnected with the transmission gears of the vehicle in a well known manner.

The motor-generator 33 is constructed and arranged to serve as a motor, for starting the engine and as a generator for charging the accumulator or storage batteries. This motor-generator is controlled as to its status, as a motor, or generator, by a clutch pedal or operating member 32.

The means by which the clutch pedal controls the status of the motor-generator, will now be described, referring to Figs. 1, 4 and 5: Adjacent to one end of the clutch shaft 31, the bracket 34 is loosely mounted thereon; that is, the said bracket normally permits relative oscillatory movement of the clutch shaft 31, but is held in fixed position, relative to any transverse or lateral movement thereon. This bracket is provided with an arm 35, having a bearing, which receives the stem 36, of the magnet 37. The stem 36 not only acts as a means for securing the magnet to the bracket 34, but also forms the core of the magnet. The bracket 34 also is provided with a forwardly extending portion 38, to the outer end of which the armature or latch 40 is pivotally secured at 41. One end of the armature 40 is normally positioned in alignment with, but spaced from the core 36 of the magnet 37 (see Fig. 4). The opposite end of the arma-

ture 40 is formed in the shape of a hook or latch, as at 42, and is adapted to engage, when the armature is moved into the position shown in Fig. 4, with the curved arm 43, which in turn is secured to the clutch shaft 31, by means of a key or suitable locking device 44.

Under certain conditions, it will be advisable to adjust the armature so as to either 10 decrease or increase the space between the contact end of the armature and the magnet 37, and as one means for accomplishing this object, I have provided a thumb screw 45, which by being adjusted against a projection 15 46, formed on the arm 38, will adjust the armature into the desired position. A small coil spring 47 normally tends to hold the armature in disengaged position, as shown in Fig. 5.

20 The arm 35 of the bracket 34 has a pivotal connection with the link 48, which extends rearwardly and is connected to the straight arm lever 49, which in turn is rigidly mounted upon the vertical shaft 50.

25 The bracket or supporting member 51 is rigidly secured on the cross brace 52 and forms the support for the vertical shaft 50. An operating rod 53 is connected with the opposite end of the straight arm lever 49, and extends forwardly and is connected with the shiftable or coupling gearing, which couples up the motor-generator and the engine, for starting purposes (see Figs. 1, 8 and 9).

30 Inasmuch as it is desirable to shift the controller switch, which selects the electrical connections between the accumulator and motor-generator, with substantially the same operation as that which shifts the coupling means between the motor-generator and the engine, suitable mechanisms are arranged, which are operated by the same movement of the clutch pedal as that which shifts the coupling means between the engine and motor-generator. These combinations of mechanisms are clearly shown and described in detail in my heretofore mentioned co-pending applications and therefore no detail description or showing thereof will be 45 made in the present case.

The above named mechanisms are connected up to the connections above described, by means of a small link 54, mounted upon and movable with the vertical shaft 50 (see Fig. 1) which is connected in turn with the controlling or operating rod 55, which engages with and is connected to the mechanisms described in my co-pending application, for shifting the controller from charging position to starting position and vice versa.

55 Referring for the present to Figs. 2 and 5, it will be seen that the magnet 37, which as has been explained, is normally loosely mounted upon the clutch shaft 31, is in-

cluded in a circuit which is independent of the operation of the controller switch and which will be designated hereinafter as the "independent circuit." This circuit connects with the multiple series connections 70 between the accumulator and generator, and is normally open, inasmuch as it is not desirable to have current passing through the said circuit, during the normal operation of the engine, that is, this circuit is only 75 closed for imparting a relatively slow initial turning movement to the motor and to also effect the coupling up of the operating member 32 with the connections for shifting the means for coupling up the engine and motor-generator. 80

As has heretofore been stated, one of the objects of the present invention is to provide means for controlling this initial movement of the motor-generator and the connecting up of the means for shifting the coupling gearing between the motor-generator and the engine, with the operating member through the medium of the lever which ordinarily is only used to effect the advance 90 or retard of the spark timer mechanism in ignition systems, such as are in use on automobiles at the present time.

95 One embodiment of the means whereby the above object is attained, that is, the control of the independent electrical circuit which is adapted to impart a slow initial turning movement to the motor and to also connect up the means for coupling up the engine and motor-generator with the operating member or clutch pedal, will now be described together with the structure of the steering mechanism and the throttle valve control.

100 The steering mechanism proper, comprising the hand wheel 300 and the ordinary hollow steering post 301, which is secured to said wheel by means of the arms 302^a, is of substantially the standard type now used in automobiles.

105 The "throttle lever" which controls the position of the throttle valve and consequently the supply of fuel to the engine, is mounted in the usual manner upon the steering mechanism, and comprises the lever 302, rigidly secured to the tubular rod 303, shown in dotted lines in Fig. 3, as being journaled within the post 301. At the lower end of this tube or hollow rod 303, a suitable beveled gear wheel 304 is attached, which meshes with the beveled pinion 305, which in turn is rigidly mounted on the lower end of the sleeve 306, to which is fastened the rod 307 ("broken away") in Fig. 3. This rod is normally connected with the throttle valve, by any suitable mechanism (not shown); and upon the actuation of the said rod, through the medium of the throttle lever 302, and the beveled gear arrangement 110 which tends to oscillate the sleeve 306, the 115

throttle valve will be opened or closed as desired, in accordance with the movement of the lever 302.

Within the tubular rod 303, a rod 308 is 5 rotatably journaled, carrying at its lower end, a beveled gear wheel 309, which meshes in turn with the beveled pinion 310, rigidly mounted on the vertically disposed shaft 312, held in its proper position by means 10 of the bracket plate 313, which also supports the sleeve 306. This upwardly disposed rod 312 carries a link 314 (see Fig. 1) which extends forward and connects with the lever projecting from the timer and distributor mechanism of the ignition system 15 of the engine (see Fig. 1).

The mechanism heretofore described relative to the structure for effecting the adjustment of the throttle valve and also for 20 effecting the advance and retard of the spark, by adjusting the timer mechanism, simply constitutes a conventional form for accomplishing these functions and one which is in general use.

25 As a means for adjusting the timer mechanism to secure the advance and retard of the ignition spark, the lever 315 is rigidly mounted on the upper end of the rod 308 and is adapted to be oscillated back and 30 forth over the sector 316, which in turn is mounted upon the support 316^a and which also provides a guide or track-way for throttle lever 302. The adjustment of each 35 of these levers is effected manually by the operator of the vehicle.

As shown in Fig. 6^a, the spark control-lever 315 is provided with the spring pressed stud, which engages with the sector 316, said engagement creating such frictional resistance 40 that the free movement of the spark control-lever relative to the sector will be prevented from inadvertent or accidental adjustment. The inner edge of the sector from "home position" to "initial starting 45 position" is cut away, as at 318, (see Figs. 6 and 6^a), so that when the spark control-lever is moved back of "home position", practically no frictional resistance will be 50 encountered by the movement of the lever, inasmuch as the spring pressed stud will no longer be in engagement with the edge of the sector. The advantages of providing 55 this cut away portion on the sector 316 will appear more clearly with the description of the mechanism cooperating with the spark control-lever, to effect the opening and closing of the independent electrical circuit which controls the initial movement of the starting device or motor.

60 Figs. 7 and 7^a show a modified form of the means whereby the adjustment of the spark control-lever 315, from "home position" to the "initial starting position" may be secured. Referring particularly to Fig. 65 7^a, it will be seen that the projecting ledge

342 is secured to the quadrant 344, so as to provide an absolute and positive stop for the spark control-lever 315, at "home position". When, however, it is desired to move the spark control-lever into "initial starting position", the button 345 is pressed rearwardly 70 so as to retract the spring pressed engaging member 346, which is mounted in the hollow end 347, of the said lever and normally maintained in engaging position, by means of the coil spring 348, until the said engaging member is sufficiently retracted, so that it will be free to ride over the ledge portion 342.

Mounted on the bracket 313, there is secured a switch box or casing 319, one wall thereof, as indicated by the numeral 320, being formed integral with the bracket member 313. On the inner face of this wall is secured a pair of oppositely disposed contact members 321 and 322, the contact member 321 being resilient, while the contact member 322 is substantially rigid. These contact members are inclosed by means of a cover 323 which is secured to the wall 320 80 in any suitable manner. Adjacent to the contact ends of the plates 322 and 321, a tubular projection 323^a is formed in the cover 323, and is adapted to receive a push button 324, one end thereof projecting outwardly beyond the termination of said tubular projection. This push button is normally held in position by means of the coil spring 327 which is mounted on the shank 90 of said button, between the annular shoulder 100 325, formed on said shank and the ledge portion 326, carried by the cover 323. In order to facilitate the assembling of this push button, the contact end thereof is made independent from the shank portion and 105 may be secured thereto, in any suitable manner, such as for instance, by providing the contact member with the small stem portion adapted to fit within a bore formed in the end of the shank portion.

110 As a direct means for operating the push button against the resistance of the spring 327, the curved arm 328 is rigidly mounted upon the vertically disposed shaft 312, which as has been stated, heretofore, is oscillated in accordance with the movement of the spark control-lever. This curved arm 328 is provided at its free end, with the adjustable thumb screw 328^a, so that the distance between the end of the push button and the 115 said thumb screw may be regulated to suit conditions, that is, to determine the distance that the spark control-lever 315 must be moved back of "home position", in order to effect the closing of the contact members 120 321 and 322 for the purpose specified hereinafter.

In the embodiment shown herewith, the sector or quadrant is provided with a like point, which may for convenience be design- 130

nated as "home position", (see Figs. 6^a and 7^a). However, in this embodiment, this "home position", does not indicate a limit of movement of the spark control-lever in either direction, inasmuch as this lever is capable of a limited further movement beyond said "home position", in a direction, whereby the ignition spark will be further retarded. The movement of the spark control-lever in this case, however, is not primarily intended to secure further retardation of the ignition spark, but is designed to effect the closing of the independent electrical circuit through the bringing in contact of members 321 and 322. The contact of these members is effected by the oscillation of the shaft 312, through the medium of the spark control-lever 315, beyond its "home position", into what might be termed "initial starting position", and the consequent shifting of the curved arm 328, into such position that it will tend to force the push button 324 inwardly against the compression of the spring 327 and thus effect the closing of said contact plates 321 and 322. Thus, the cut-away portion 318, previously referred to and shown in Fig. 6^a, gives a free movement to the spark lever 315, but the operator feels the resistance of the push button 324, under the influence of its spring 327, so that he immediately knows when the lever has been thrown back to this position, that this resistance to the further movement of the spark lever indicates that he has reached the position where the continued movement of the lever will operate the push button to cause the spark lever to perform the functions described in connection with the starting operation.

Referring to Figs. 2 and 5, it will be noted that the contact plates 321 and 322 are included within the independent electrical circuit which connects with the multiple series connections between the generator and accumulator and normally maintain this circuit in an open condition.

In Fig. 2, one line of the electrical circuit is designated by the numeral 63, which connects with the contact plate 321, while the oppositely disposed contact plate 322 is connected with the branch wire 68, leading to one end of the coil or winding 69 of the magnet 37, which as has heretofore been described, is loosely mounted upon the clutch shaft of the vehicle. The opposite end of the magnet coil 69, is connected with the series field of the motor-generator, through the wire 70. The arrangement of the connections of this independent electrical circuit, permit the carrying out and accomplishment of a various number of novel functions, one of which will now be set forth.

Supposing that the engine 21 (see Fig. 1) is at rest and that the coupling or multi-

plied gearing which constitutes the driving connections between the motor-generator 33 and the said engine, is in disengaged or non-driving position, and that it is desired to start the engine 21, the spark control-lever 315 is moved over the quadrant 316, until it registers with the point designated "initial starting position". This movement of the spark control-lever will, of course, cause the bringing together of contact plates 321 and 322, whereby the independent electrical circuit through the magnet 37 will be closed, and inasmuch as this circuit leads from the motor-generator to the multiple series or parallel connections of the accumulator, the current that will pass through the said circuit, will be of substantially the same voltage as that at which the accumulator is charged, when the motor-generator is being driven as a generator, for charging purposes. The current passing through this independent circuit will instantly energize the magnet 37, whereby the contact end of the pivoted armature or latch 40 will be attracted to the magnet core or stem 36, against the tension of the spring 47. Upon the movement of the contact end of the armature, the latch end 42 thereof, will consequently be swung outwardly and into engagement with the curved arm 43, which as has been explained, is rigidly connected to the clutch shaft 31. By the construction of the interlocking portions of the latch mechanism 42 and the curved arm 43, it will be understood that upon said elements being brought into interlocked position and pressure being applied to the clutch pedal, it will no longer be necessary to continue the passage of current through this independent circuit, that is, providing the coupling gearing between the motor-generator and the engine has been brought into coupled position, inasmuch as the latch portion 42 and the curved arm 43 will be held in interlocked position by mechanical means. By the above arrangement, it will be obvious that the magnet 37 and bracket 34, together with the lever and link connections thereof, will be secured in fixed relation to the clutch shaft 31 throughout the engagement of the latch portion 42, with the fixed arm 43.

As soon as the armature 40 and the fixed arm 43 are in interlocked position, the operator of the vehicle will move the spark control-lever 315 into any proper position, in the same manner that the spark control-lever is adjusted at the present time on automobiles for the starting operation of the engine. However, if the operator should fail to do this and simply release the said lever 315, the spring 327 which has been compressed by the inward movement of the push button 324, will exert sufficient pressure by its expansion, as to operate the in-

termediate connections between the arm 328 and the lever 315, to cause the said lever to be automatically advanced any predetermined degree, from the point designated "initial starting position". This constitutes 5 resilient or spring means for forcing the spark lever out of its initial starting position, in case it should inadvertently otherwise be left there. In the ordinary operation of this system, the operator maintains 10 the spark control-lever in its initial starting position, until the multiplied or coupling gearing between the motor-generator and engine has been brought into coupled position. 15 Inasmuch as the electrical circuit, wherein the magnet 37 is included, connects with the series field of the motor-generator, it will be understood, that the current passes 20 into the series field and tends to operate the motor-generator as a motor, at a voltage of substantially six volts, this together with whatever effect may be due to the resistance of the magnetic circuit, causes a relatively 25 low amperage, so that the motor-generator rotates slowly. Upon pressure being exerted upon the clutch pedal to move the same in a forward direction, the clutch shaft together with the magnet 37 and the link or 30 lever 48 will also be moved in like direction, said clutch, through the medium of the yoke 31^a, being consequently disconnected from its driving engagement with the fly-wheel of the engine whereby the 35 running gear of the vehicle will be absolutely disconnected from the propelling element, during the starting operation of the vehicle. Of course, in the present instance, the operating member for effecting the 40 starting operation is this clutch pedal referred to, but it will be understood that if desired, any type of operating device can be used as an operating member to connect up directly or indirectly between the starting device and the engine, or to control the 45 starting operation.

As has been stated, the forward movement of the clutch pedal necessarily imparts like movement to the lever 48, which in turn tends to shift the straight arm lever 49, and this lever by its pivotal connections with the lever 53, will pull said lever 53, rearwardly, and thus tend to bring the multiplied gearing of the motor-generator into 50 position, to mesh with the driving gear of the engine. This multiplied gearing seen in Fig. 9, comprising a small pinion 71, is mounted upon the shaft 72, which in turn has a flexible connection 53^a with the rod 55 or lever 53. The function of this flexible connection and the specific structure thereof, has been clearly described and shown in my co-pending application bearing Serial Number 633,443, filed June 15, 1911, and 60 therefore further description will be omitted 65

in the present case. The small pinion 71 is adapted to engage with the fly-wheel gearing of the engine and is connected with the larger pinion 73, which engages with and is driven by the motor pinion 74 of the motor-generator.

During the intervals that the multiplied gearing, comprising the pinions 71 and 73, is out of driving connection with their respective gear wheels, the gear teeth of the 75 respective enmeshing gears, may rest in such a position, that the end faces of the co-adjacent teeth of the respective enmeshing gears, may be out of their proper alinement, that is, they may be in such position, that when the multiplied gearing is moved to enmesh the said gears, the end faces thereof, will come in conflict. By the initial rotation of the motor-generator, as a motor, at a low speed, this difficulty is overcome, inasmuch as the motor gearing 74 will be 80 slowly rotated, and the pressure exerted on the multiplied gearing, will cause the large pinion 73 thereof, to readily mesh with the pinion 74. By referring then to Fig. 8, it 85 will be seen that the clearance between the small pinion 71, of the multiplied gearing, and the fly-wheel gearing, is greater than the clearance between the large pinion 73 and the motor driven pinion 74. The object in having a variance in the clearance at these points, is to permit the picking up and rotation of the multiplied gearing by the motor-gear wheel 74, before the enmeshment of the pinion 71, with the fly-wheel; 90 this action tending to facilitate the shifting of the gears into coupled position.

When the clutch pedal 32 is operated, as has been described above, to connect or couple up the coupling, or multiplied gearing, with the motor pinion and the fly-wheel gearing of the engine, it is desirable to also shift the controller switch, so as to change the electrical connections of the system from their normal charging position, whereby the 105 accumulator and motor-generator are connected in series multiple, to the starting position, in which position the accumulator and the motor-generator are connected in series, so that the motor operates as a 110 straight series motor.

The manner of shifting the controller switch from charging to starting position has been clearly described and shown in my co-pending application, Serial No. 633,443, filed June 15, 1911, as including means for connecting the controller switch with the clutch shaft 31 of the automobile. The means of connecting the controller switch with the clutch shaft, and consequently with the clutch pedal is fully described hereinafter. By shifting the electrical connections between the accumulator and the motor-generator, from series multiple to series, current of an increased or multiplied volt- 120 125 130

age will be introduced into the motor-generator, causing the said motor to instantly operate, at a greatly increased speed. The motor, operating at a high rate of speed 5 will tend to turn the engine slowly through the medium of the multiplied or coupling gearing, which connects the motor-generator with the engine.

The engine, when once it becomes self-10 actuating, quickly increases in speed and because of the ratio between the engine fly-wheel gearing and the coupling gearing and motor pinion would soon tend to drive the motor-generator, at a prohibitive speed. 15 The means for preventing the existence of conditions of this character, have been fully explained in my copending application, Serial Number 621,512, filed April 17, 1911, and will not therefore be described in the present 20 case. However, as soon as the engine has become self-actuating, a suitable clutch mechanism will connect the motor-generator, as a generator, with a train of gears, located at the front end of the engine, which may be 25 termed, "generator gearing." This operation of the motor-generator as a generator, is secured in the following manner. The front end of the crank shaft of the engine is provided with a gear wheel 225, which 30 meshes on one side, with the pinion 226, to operate the cam shaft of the engine and thus actuate the engine valves in a well known manner. This gear wheel 225 also meshes on the opposite side with the intermediate gear 227, which in turn drives a 35 pinion 228, secured to the end of the shaft 27.

Inasmuch as it has been found advisable 40 to drive the motor-generator, as a generator, at substantially engine speed, the size of these connecting gear wheels is such that the armature of the motor-generator and the crank shaft of the engine will be operated at a substantially, one to one ratio.

45 The shaft 27 has heretofore been utilized to drive the magneto, on a car of this type, and also to operate the oil pump. Because of a previous existence of a shaft of this character, in a car of this type, it has been 50 found advantageous to use this shaft as one connecting means for one set of gearing between the engine and motor-generator.

55 Referring to Figs. 10 and 10^a, it will be seen that the shaft 27 passes through the oil pump 26 and on one end, as has been heretofore described, there is secured the small pinion 228. Adjacent the opposite end of said shaft, a collar 229, is rigidly secured by means of the pin or key 230. This collar 60 is mounted a short distance from the end of said shaft, so as to leave a short section thereof, to enter into a bearing formed in the ratchet member 231 of the friction roller clutch 232, which connects up the motor-generator with the shaft 27, when the motor- 65

generator is to be run by the engine, as a generator for charging purposes. The ratchet member 231 of the roller clutch 232, has an annular collar extending therefrom, provided with oppositely disposed slots or 70 recesses 240, wherein lugs 233, formed on the collar 229, shown in dotted lines in Fig. 10^a, fit, and thus secure the shaft 27 to the ratchet member 231. The ratchet member is provided on its periphery, with a plurality 75 of beveled depressions 235, wherein friction members 234 of either the ball or roller type are placed. These friction members have suitable small springs 241, mounted on the ratchet member 231, which normally tend to 80 force the said members into the proper position.

The motor-generator shaft 237 (see Fig. 10^a) is extended outwardly from the casing of the motor-generator and is keyed to an 85 annular casing 238, by means of the pin or key 239. This casing 238 forms one of the coöperating members of the friction roller clutch and is adapted to receive the ratchet member of the clutch 231, as is clearly shown 90 in Figs. 10 and 10^a.

A small cover plate 244 fits over the annular collar of the ratchet member 231 of the roller friction clutch and is secured to the casing 238, by any suitable means, such 95 as the small screws 245, and prevents the entrance of dirt, etc., into the moving parts of the clutch. The operation of this friction clutch is as follows: When the motor-generator is connected with the engine, as a motor, 100 to start the same, the armature or motor-generator shaft 237 will of course, be rotated and will carry with it the friction clutch casing 238, in the direction shown by the arrow in Fig. 10. This will permit the casing 105 238 to rotate freely, relative to the ratchet member 231, inasmuch as the friction members 234 will be maintained in the enlarged portions of the depressions 235. However, as soon as the engine becomes self actuating 110 and the crank shaft is revolving, the generator gears, comprising the gears 225, 227 and the pinion 228 will drive the magneto shaft and as soon as the speed of the engine picks up, the ratchet member 231 of the friction 115 clutch will be carried forward in the direction of the arrow as shown in Fig. 10, thus moving the members 234 into the V-shaped portion of the depressions or recesses between the ratchet member 231 and the interior of the casing 238, thereby coupling these 120 two members together, through the friction of the members 234, so that the armature of the motor-generator will be driven by the engine, in such a manner that the motor-generator will be operated as a generator, 125 for charging purposes.

In order to compensate for any slight inaccuracy in the lining up of the generator with the operating shaft 27, a coupling, pref- 130

erably of the Oldham type, designated by the numeral 27', formed by the parts 229 and 231, as stated heretofore, is interposed between the oil pump and the clutch mechanism 232. If any slight inaccuracies occur in the alinement of the coöperating elements, that is, between the shaft 27 and the generator, this coupling will compensate therefor and permit the free operation of the generator, regardless of the slight inaccuracy.

As soon as the engine becomes self actuating, the operator of the vehicle releases the pressure upon the clutch pedal, and by means of the spring arrangement, described hereinafter, the clutch pedal together with its shaft and the controlling mechanism, is brought back into normal position, whereby the transmission clutch will be moved into engagement with the fly-wheel of the engine and the vehicle will be ready to start, as soon as the proper adjustment of the transmission gearing has been made.

With the addition of the several connecting elements, which are carried by the clutch shaft and operated by the movement of the clutch pedal, it has been found advisable to supplement the action of the ordinary spring which tends to return the clutch pedal to normal position, by means of an additional spring 85, of suitable strength, one end of which is secured to the end of the straight arm lever 49, which connects with the link 48, whereby said spring will be tensioned, by the forward movement of the lever 49. As soon as the pressure is released from the clutch pedal, the said spring 85 will tend to return the several elements to their normal position.

The shifting of the controller-switch, from starting position to its normal charging position, is accomplished positively, in the manner set forth in my copending application, filed June 15, 1911, Serial Number 633,443.

The circuit connections and means for rearranging the batteries so that they are connected in series with the motor-generator for starting purposes, and in multiple series for charging purposes, is clearly shown in Fig. 2. By referring to this diagrammatic Fig. 2, it will be noted that the motor-generator comprises a series winding 103 and a shunt winding 102. This shunt winding is cut out during the starting operation, whereby the motor-generator will operate as a series motor when the batteries are connected in series. Now when the motor-generator is operating as a generator for charging the batteries in multiple series, both the series and shunt windings are brought into operation as is described more specifically hereinafter. In this connection, it may be stated that the controller-switch which is substantially the same as that described in detail, in my copending applica-

tion, filed April 17, 1911, Serial Number 621,512, will not be described, other than as in the diagrammatic showing in Fig. 2, inasmuch as the detail structure thereof, does not enter into the present invention, except as has heretofore been stated.

The arrangement of the storage batteries, which form the accumulator, is shown at the right, in Fig. 2, with the batteries grouped in four sets of three cells each. This makes 12 cells in all, which at the approximate voltage of two volts each, gives practically 24 volts, when the cells are connected in series. As has heretofore been stated, these cells are connected in series, to give this 24 volts for starting purposes, that is, for driving the motor-generator as a motor, to start the engine. Whereas in charging, the cells are arranged in multiple series, having four groups or units each unit comprising three cells in series and these groups being arranged in parallel for charging, so that the charging takes place, at practically six volts.

In the arrangement of the connections shown in Fig. 2, for accomplishing the shifting of the storage batteries in this manner, the dotted line connections represent the positions of the shifting switch controller, when the device is arranged for charging, while the heavy line connections represent the positions of the switch-controller, for the starting arrangement, that is, when the batteries are all in series.

The motor-generator 33, comprises a shunt compound differential round machine, having a rotating armature 101, provided with the shunt and series fields 102 and 103 respectively.

One of the lead wires 104 extending from the shunt winding of the motor-generator, connects with the contact point 105 which is shown in Fig. 2, as being connected by the dotted line or electrical connection 106, which it will be understood, only connects said wire 104 with the wire 107, when the motor-generator is being employed as a generator for charging purposes. The solid black line or electrical connection 108, illustrating the position into which the connection 106 is shifted, when the motor-generator is operating as a motor. It will therefore be seen that the solid lines and the dotted lines really represent one and the same element, shiftable into two distinct positions.

The lead wire 109 extends from the point 110 to form the common wire for connecting up one side of the batteries, when arranged in multiple series, for charging purposes. At the point 110 on this wire 109, there extends downwardly, a lead wire 112 which connects with the contact strip 113 which is embodied in the automatic cut-out device. The armature 114 of this cut-out device is

connected to the coil 115, to which the opposite end of the coil 116 is connected by means of the short branch wire 117, leading from the line wire 120, while the other end 5 of this coil 116 is connected to the other line wire 118 of the system. The armature 114 is normally held out of engagement with the contact strip 113 by means of a small spring 119 (see Fig. 2). The function of this cut-out device will now be described. 10 When the motor-generator 33 is being employed as a generator, to supply current to the accumulator or storage batteries, the rotation of the armature 101 thereof, causes 15 the current to build up in the shunt field 102 and gradually to also enter and build up in the series field 103 to such a point that a balancing effect will be obtained between the two fields. The initial flow of current 20 through the series field and wire 120, first has to enter the high resistance coil 116, inasmuch as the armature is in open position, and will continue in this path until the core 121, of the cut-out device has become energized 25 sufficiently to attract the armature 114, against the resistance of the spring 119. The initial flow of current from the generator is therefore through the series coil or field 103, wire 120, through the high resistance coil 116, branch wire 122 into the 30 main line wire 118, back into the opposite side of the generator. The resistance of the coil 115 is much lower than that of the coil 116 and therefore, as soon as the core 121 35 of the cut-out device has become sufficiently energized to attract the armature 114, thus making the contact between the said armature of the contact plate 113, the current will pass through the low resistance coil 115, the 40 armature 114, contact plate 113, wire 112 to the common line wire 109, instead of passing through the high resistance coil 116. This cut-out device operates to prevent the 45 current, from the storage battery, discharging back through the generator, in case the generator should slow up, so as to reduce this current by the slackening of its speed. That is, the kick back of the current, from 50 the storage battery, running through coil 115 reversely, would break the circuit connection between the armature 114 and the strip 113, the armature being immediately restored, to its open position, by means of the spring 119. This cuts the storage battery 55 out of the generator circuit and leaves the generator circuit running through the high resistance coil 116, wherein the current is now too weak, on account of the slow speed of the generator, to energize the core sufficiently to restore the contact between 60 the strip 113 and the armature 114.

Going back to the battery connections, it will be seen that when the cut-out device is closed and the current is passing therethrough, into the wire 112 and wire 109, it

will be distributed among the various groups of cells or units of the storage battery. In Fig. 2, it will be seen that the branch wire 125 leads from the point 126, on the wire 109 to the point 127. This point 70 is connected by the dotted line or electrical connection 128, to the contact point 129. From this point 129, the connecting wire 130 extends to the positive pole of the left-hand set or unit No. IV, of the storage 75 battery. The four different sets of cells are designated by Roman numerals, in Fig. 2, also with their positive and negative terminals, for the sake of convenience. From the opposite side of this set of cells or unit 80 No. IV, the lead wire 131 extends downwardly to and connects directly with the wire 118, which in turn leads back to the motor-generator.

Leading from the contact point 129, is a 85 heavy line or connecting strip 132, which connects with the contact point 133. As previously stated, this heavy line connection 132 represents the shifted position of the dotted line connection 128 and vice-versa. 90

The lead wire 134 connects the contact point 133 with the contact point 135, which is located on the opposite side of the third set of the accumulator cells or unit No. III. From this point 135, a dotted line connection is shown connecting with the contact point 137, which in turn, is connected by the wire 138 to the line wire 118. The heavy line connection 139 indicates the shifted position of the dotted line connection 136, 100 when the connections of the battery are shifted, from charging to starting position.

Without repetition of the details of the connections of the other sets of cells of the storage battery, it is thought that a brief 105 description will make clear, just what the system of connections is, making use of the dotted and heavy lines, for the respective shifting positions. It having been stated that the heavy lines of these V-shaped shifting elements, represent the positions of those parts for the starting operation, it will be assumed first, that the heavy lines in such cases represent the actual connection, there being no cross connections. The circuit may, for instance, start at the lower side of the right hand set of batteries or cells, that is, set No. I, the current running through the lead wire 150 to the point 151, thence through the connecting wire 152 to the point 110 153, which is connected by the heavy line connection 154, to the wire 155 which connects with the opposite or positive terminal of unit No. II, thence across the battery through the wire 156 to wire 157 and thence 115 into the unit No. III, through the medium of the heavy connecting strip 158 and wire 159. The current then passes through the unit No. III, into the wire 160 through the point 135, wire 134, heavy connection 132, 120 125 130

- wire 130, through unit No. IV, into wire 131, thence through the main line 118 into the motor-generator 33, thus operating the motor-generator as a motor, under the combined voltage of all of the units of the battery. The circuit is completed through the series field 103, wire 120, branch wire 162, which short-circuits the cut-out device heretofore mentioned, through the heavy connecting strip 163, into wire 109, through which it passes into the positive side of unit No. I. When in this connection, it will be noted that the shunt field or winding is cut out, because of the gap, which is represented by the dotted line 106. This arrangement causes high voltage through the motor for starting and a straight series wound motor to give torque, for the purposes, and with the advantages heretofore referred to.
- Immediately upon the motor-generator creating sufficient power to turn or crank the engine and thus automatically start the same, the mechanical switch or controller is shifted, as has been heretofore explained, through certain mechanical connections, so that the series connections of the accumulator are withdrawn and the connections for the charging operation are drawn into place. This condition of the switch or controller as shown in the diagrammatic connections of Fig. 2, for the charging operation will now be explained.
- Starting at the generator the current divides into two circuits, the first of which passes into the shunt field through the wire 107, through the dotted line or electrical connection 106, wire 104, shunt field coil 102, wire 104 into the opposite brush of the generator. This energizes the shunt field. The other divided circuit starts from the positive brush of the generator through the series coil 103 to the lead wire 120. Until the engine speeds up there is not sufficient current passing into the coil 116 to attract the armature 114, through the core 121. The current will therefore pass through the coil 116, wire 122 into the main line wire 118 thus making the complete circuit. As soon as the engine speeds up and the series and shunt fields of the generator have been brought to a point where the voltage is sufficient to overcome the battery voltage, then sufficient current will pass through the coil 116, of the cut-out device, to energize the core 121, to such a degree that the armature 114 will be attracted thereto and thus make contact with the plate 113. As soon as this action occurs, the current will immediately pass through the low resistance coil 115, thence through the armature and contact plate 114 and 113 respectively, into the wire 112 and into the line wire 109. From thence the current flows through the wire 125, through the dotted line connection 128, wire 130, through the fourth unit of the

battery, out through the wire 131 into the main line wire 118, and thence back to the generator. At the same time the other three units of the battery are being charged in substantially the same manner, by reason of the fact that from the common wire 109 there extends the lead wires 175, 176, to the upper side of the said groups of cells, while the lower sets of these groups are connected to the main line wire 118, through the wires 150, 156 and 160, dotted line connections 180, 181 and 136 and branch wires 185, 187 and 138 respectively. Thus under these dotted line connections, it being understood that the heavy line connections are eliminated when the system is in charging position, the generator is now in its condition for charging the batteries in multiple series arrangement of four groups in parallel, with three cells in series in each group, and the generator has its field wound with a shunt-compound differential winding arrangement.

The above described connections for operating the motor-generator as a motor, at a multiplied voltage at 24 volts and to permit the motor-generator to act as a generator, to charge the accumulator at substantially six volts, are absolutely controlled by the shifting of the controller switch.

As has heretofore been stated, there is an additional electrical circuit connection between the accumulator and motor-generator, which is provided so that the motor-generator may be operated as a motor, at a reduced voltage, as compared with the voltage at which the motor-generator operates as a motor for starting purposes, or at substantially the same voltage as that at which the accumulator is charged by the motor-generator, acting as a generator, namely six volts. This electrical connection or circuit, comprises wire 63, which is tapped off of the main line wire 109, and lead to the contact plate 321. The contact plate 322, which is mounted within the switch box 319, is oppositely disposed to the contact member 321 and is suitably insulated therefrom. The lead wire 68, extends from the contact plate 322 to the magnet coil 69, the opposite end of which is connected with the series field of the generator, by means of the wire 70.

The entire circuit just described and which is adapted to be closed and opened, as has heretofore been described, by means of the adjustment of the spark control-lever of the ignition system, is of a higher resistance than the circuit which conducts the current from the cut-out device to the batteries, through the wires 112 and 109 respectively, and inasmuch as the magnet, which is included in said circuit, comprises the coil 69, it will follow that the resistance in said circuit is such that the amount of current passing through said circuit, will be reduced be-

low the amount of current which is normally charged into the accumulator, when the motor-generator is operating as a generator, under normal conditions. The difference in resistance, between this additional electrical circuit and the charging circuit, also effectually provides a safety device, inasmuch as the flow of current through this circuit will be practically negligible; that is, this flow of current will be insufficient to operate the armature 40, even though the circuit is closed through the operation of the spark control-lever, at any time while the motor-generator is operating as a generator, or at least at any time while the cut-out device is closed, to permit the passage of current therethrough. This same arrangement, consequently acts as a safety device for preventing the coupling up of the mechanical connections and the operation thereof, at any time except when the motor-generator and the engine itself is at rest or the cut-out device is open. Therefore, when the engine is running, even though the spark lever should be thrown back to the initial starting position, no trouble arises therefrom, because the starting functions of the spark lever, as above referred to, then become disabled because of the circuit conditions described. From the connections of this additional or supplemental electrical circuit, it will be understood that the closing of the switch by the operation of the spark control-lever, is necessarily the initial operation of the system and takes place while the controller switch is in charging position, so that current under the voltage of the several units in multiple series, is permitted to pass through this circuit into the motor-generator, to operate the same at a low voltage, for the purposes hereinbefore set forth.

While I have set forth the various operations of the system as the description has progressed, a brief description will now be given of the sequence of operations, as they occur when it is desired to start the engine of the vehicle.

Supposing that the motor-vehicle, together with the engine and motor-generator are at rest, and that the connecting elements thereof, are in their normal or home position, the operator of the car first shifts the spark control-lever, which is mounted upon the steering wheel, over the sector or quadrant, until it registers with the point designated as "initial starting position." This action closes the initial starting circuit and causes the current to be introduced into the motor-generator, to actuate the same at a low voltage. The passage of current through this circuit, also causes the connection or coupling up of the interlocking mechanism, which is mounted upon the clutch shaft, with the clutch pedal or main

operating member. As soon as this interlocking or controlling mechanism has been brought into locked position with the clutch shaft, pressure is applied to the clutch pedal or operating member and with the forward movement thereof, the shifting gears which couple up the motor-generator with the engine, are brought into enmeshment, and the controller switch subsequently is shifted from charging to starting position. Simultaneous with the coupling up of the motor-generator and the engine and therefore previous to the shifting of the controller switch from charging to starting position, the transmission clutch, which connects the driving gear of the vehicle with the engine, is positively disconnected from driving connection with the engine. Immediately upon the controller switch being shifted into starting position, the current under the combined voltage or through series connections, passes into the series field of the motor-generator and actuates the same, at a multiplied voltage, with sufficient power to turn or crank the engine and thus automatically start the same. As soon as the coupling or shifting gears, between the motor-generator and the engine have been brought into coupled position, the operator may move the spark control-lever over the quadrant to the most advantageous position, for starting, without affecting the connections between the interlocking mechanism and the clutch shaft. The reason for this will be obvious, inasmuch as the construction of the interlocking elements is such that once they have been brought into interlocked position and pressure is applied, to the operating member, the said parts will be mechanically maintained in their interlocked position, until such time as the pressure is released from the clutch pedal. Upon the engine becoming self actuating, the operator may release the pressure from the clutch pedal or operating member, which will automatically be returned to its home or normal position, by means of any suitable spring arrangement, whereby the transmission clutch, which has been held out of engagement with the engine, will be returned to its driving connection with the fly-wheel of the engine. The release of the pressure from the clutch pedal and the adjustment of the spark control-lever, away from the point designated "initial starting position", will of course, cause the spring 47 (see Figs. 4 and 5) to automatically disengage the interlocking mechanism, loosely coupled on the clutch shaft, from its engagement with the elements rigidly secured to said clutch shaft, inasmuch as the circuit which controls this interlocking mechanism, is instantly broken, upon the removal of the spark control-lever, from the "initial starting position" and the mechani- 130

cal connection between these elements is instantly released, upon pressure being removed from the main operating member. Simultaneously with the return of the clutch pedal to its home position, the gears which couple up the motor-generator and the engine, will be forced out of their driving position, and the controller switch will so be shifted that the series connections will be broken and the charging connections brought into operative position. The transmission clutch will also be forced back into engagement with the fly-wheel of the engine. After the engine has been started and the connections shifted, as just described, it will be obvious that the transmission clutch of the engine may be connected and disconnected from engagement with the fly-wheel of the engine, without affecting in any way, the other mechanism, inasmuch as this mechanism is normally loosely mounted on the clutch shaft and is only brought into operative position, at such times as the magnet 37 is energized, under which condition it causes the coupling up of the pedal shaft with the magnetic device.

While the system, herewith shown and described, together with the combination of mechanisms embodied therein, is admirably adapted to fulfil the objects primarily stated, it is to be understood that it is not desired to confine the invention to the form of embodiment of the invention here disclosed, inasmuch as it is susceptible of embodiment in various forms, all coming within the scope of the claims which follow.

What I claim is as follows:

1. In an engine starting device, the combination with an engine, including an ignition system therefor, and a spark controlling lever for said ignition system; of a starting device for said engine; means for coupling said starting device to said engine; an operating member for controlling said coupling means, normally disconnected therefrom; and means controlled by said spark control-lever for effecting the connection of said operating member to said coupling means.

2. In an engine starting device, the combination with an engine, including an ignition system, and a spark controlling lever for said ignition system; of a starting device for said engine; means for coupling said starting device to said engine; an operating member for controlling said coupling means, normally disconnected therefrom; and electrical means controlled by said spark control-lever for effecting said connection of said operating member to said coupling means.

3. In an engine starting device, the combination with an engine, including an ignition system and a spark control-lever for said system; of a starting device for said

engine; means for coupling the engine and starting device together; an operating member for controlling said coupling means; and means under control of said spark control-lever for giving said starting device a slow initial starting movement, as a preliminary to the movement of said operating member to operate said coupling means.

4. In an engine starting device, the combination with an engine, including an ignition system, a spark control-lever therefor; of an electric motor for said engine; means for coupling the engine and motor together; an accumulator comprising a plurality of units; electrical series connections between the units and the electric motor, for operating the motor under the combined voltage of the accumulator, when the engine and motor are coupled together; and independent electrical connections under control of the spark control-lever, for initially operating said motor under the voltage of one of the units of the accumulator.

5. In an engine starting device, the combination with an engine, including an ignition system, a spark control-lever therefor; of an electric motor for said engine; means for coupling the engine and motor together; an operating member normally disconnected from said coupling means; an accumulator comprising a plurality of units; electrical series connections between the units of the accumulator and the electric motor, for operating the motor under the combined voltage of the accumulator, when the engine and motor are coupled together; independent electrical connections under the control of the spark control-lever, for initially operating said motor, under the voltage of one of the units of the accumulator; and interlocking means, controlled by said independent electrical connections, for connecting the operating member and the coupling means together.

6. In a motor-vehicle, the combination with an engine and running gear, comprising a steering mechanism; of a starting device for said engine; means for coupling the starting device and engine together; an operating member for controlling said coupling means; and means carried by the steering mechanism but operable independently thereof, for effecting the connection of said operating member to said coupling means.

7. In a motor-vehicle, the combination with an engine and running gear, comprising a steering mechanism; of a starting device for said engine; means for coupling the starting device and engine together; an operating member for controlling said coupling means; and electrical means mounted on the steering mechanism for effecting the connection of said operating member to said coupling means.

8. In a motor - vehicle, the combination with an engine and running gear, comprising a steering mechanism; of a starting device for said engine; means for coupling the starting device and engine together; an operating member for controlling said coupling means; electrical means for effecting the connection of said operating member to said coupling means, comprising a switch element; and means mounted on the steering mechanism but operable independently thereof for actuating said switch element. 60
9. In a motor - vehicle, the combination with an engine and running gear, comprising a steering mechanism; of a starting device for said engine; means for coupling the starting device and engine together; an operating member for controlling said coupling means; and electrical means for effecting the connection of said operating member to said coupling means, comprising a switch element having an inclosing casing carried by the steering mechanism. 65
10. In an engine starting device, the combination with an engine, including an ignition system; of a starting device for said engine; coupling means operable to couple the engine and starting device together for starting purposes; a spark controlling lever for said ignition system; and means controlled by said lever for effecting an initial movement of the coupling means, to facilitate the coupling of the engine and starting device together. 70
11. In an engine starting device, the combination with an engine, including an ignition system therefor; of a spark controlling lever capable of a range of movement from retarded to advance spark position for controlling the ignition system; a starting device for said engine; means for connecting said engine and starting device together; and means controlled by the spark controlling lever when it is moved into its retarded spark position for effecting the coupling of the engine and starting device together. 75
12. In an engine starting device, the combination with an engine including an ignition system therefor; of a spark controlling lever capable of a range of movement from retarded to advanced spark position for controlling the ignition system; a starting device for said engine; means for connecting said engine and starting device together; and means operable by the spark control lever when it is moved into its retarded position for effecting a preliminary movement of the starting device to facilitate the coupling thereof to the engine. 80
13. In an engine starting device, the combination with an engine, including an ignition system therefor; of a spark controlling lever capable of a range of movement from retarded to advanced spark position for controlling the ignition system; a starting device for said engine; means connected with said spark lever for controlling the operation of said starting device, when the spark lever is in its retarded position; and blocking means for preventing the movement of the spark lever into its position for controlling the operation of the starting device, but having provisions to release the blocking means to permit such movement. 85
14. In an engine starting device, the combination with an engine, including an ignition system and an ignition controlling element; of a starting device normally disconnected from said engine; means for coupling the engine and starting device together; and means operable by said ignition control element to effect a preliminary movement of said starting device to facilitate the coupling thereof to the engine. 90
15. In an engine starting device, the combination with an engine, including an ignition system having a spark control element; of an electric motor; means for connecting said motor to the engine for starting purposes; and means operable by the spark control element for imparting an initial operation to said motor to facilitate the coupling of the motor and engine together. 95

In testimony whereof I affix my signature in the presence of two subscribing witnesses.
